UNITED STATES PATENT OFFICE.

SARAH A. CUNNINGHAM, OF NEW YORK, N. Y.

ABDOMINAL CORSET.

SPECIFICATION forming part of Letters Patent No. 225,211, dated March 9, 1880.

Application filed January 6, 1880.

To all whom it may concern:

Be it known that I, SARAH A. CUNNINGHAM, of New York, county of New York, State of New York, have invented a new and useful 5 Improvement in Abdominal Supporters, which is fully set forth in the following specification and accompanying drawings, in which—

Figure 1 is a front and side view of my improved supporter; Fig. 2, a back view of the 10 same; Fig. 3, the improvement applied to a short corset.

A represents the corset; B, the side opening; c c c, the lifting-lacings; d d d, the eyelets; E, the securing-hook.

15 This is an improvement upon the invention secured to me, as Sarah A. Moody, under Letters Patent of the United States No. 42,591, dated May 3, 1864; and its main object is to place it within the power of the wearer to 20 control the pressure upon and support to the abdomen at will, according to the necessity found therefor from day to day, as the garment is worn and conforms by degrees to the figure it is designed to benefit and relieve, 25 the air-pads spoken of in that patent, and which were found expensive and inconvenient, being done away with and the necessity thereof of obviated by this new construction.

30 The novel leading advantages of my present invention are three in number: First, supporting the abdomen by throwing its weight very considerably upon the back; second, lacing the corset so as to bring it forcibly to the form of the person at all times, whether it 35 enlarges or recedes; third, enabling the wearer to tighten it at will when on the person, whether sitting or moving.

These important ends are attained as follows: Referring to Fig. 1 in the drawings, it 40 will be seen that the lacings extend to the front steel, and then run in and out through eyelets d d d in the front and side of the corset on an upward and outward curve, and cross each other near the middle of the back 45 just above the hips, the laces being long enough to double back and fasten in front, tightly or loosely, under hook E, so as to take the weight from the pit of the stomach.

By the upward curve the lacings are brought 50 so high as to prevent cutting the hip—a serious objection to my former abdominal corset, no matter how perfectly fitted. By the same curve, and by bringing the lacings from the back in front to fastening E, the weight, which 55 in ordinary corsets rests directly upon the hip,

is removed to the back, and the cutting is thereby prevented.

By tightening or loosening the lacings at pleasure the lower portion of the corset, forming a line around the pubis bone, is held in its 60 place under the abdomen, and the corset at all times adjusted to the form, and in no case can the corset slip up so as to fail to support the abdomen. These lacings c c c may be put from the waist to the bottom of the corset 65 at any desired distance apart, and as numerous as may be required, and either one or all may be tightened or loosened to make the corset fit any form, or to make the same corset fit as the form of the abdomen changes 70 from day to day. These improvements may be made by cutting a piece of cloth straight, or on any curve desired, by attaching strings or belts of any kind, elastic or otherwise, either to be tied, hooked, buckled, or buttoned in 75 front or at the back. These lacings, if put upon short or "long-short" corsets, so called, prevent the steel from bending out at the bottom and breaking, and also prevent the additional size often given to the figure of the 80 wearer as they draw the corset close to the body and make the same smooth and even on the outside. In short corsets the lacings would not be required to pass through the corset in and out, but could be carried along the outside of the 85 corset without any eyelets or rests whatsoever.

A great difficulty attending the use of abdominal corsets as heretofore constructed was that, however well fitted, after a few days' 90 wear there was a tendency in the body to recede and the side lacings would close and leave the corset too loose to constitute any support. This is obviated in my improved 95 corset, for the side lacings may be dispensed with altogether and the lifting-lacings not passed through the corset at all, but kept on the outside, as in a short corset.

What I claim as my invention, and desire 100 to secure by Letters Patent, is—

A corset or abdominal supporter provided with lacings running from the front steels or points near thereto, in lines of rising curvature, to the back, constructed and arranged to operate substantially in the manner and for 105 the purposes described.

MRS. SARAH A. CUNNINGHAM.
